No 269. - Design

Clute & Brothers, Assignees of
William G. Sanderson
Parlor Stove Design

Patented Feb. 26. 1858.

Ms. 269

Blute & Brothers assignees of
W. L. Sanderson of Troy N.Y.
Letters Patent No 269 Dated Feby 26th 1850.

The schedule referred to in these Letters Patent and making part of the same.

To all whom it may concern:

Be it known that I, William L. Sanderson
of Troy, in the County of Rensselaer, and State of New York, have invented or produced
a new design of ornamental parlor stove pattern, which I call the "Excelsior," and I do
hereby declare that the following is a full, clear, and exact description of the same, reference
being had to the accompanying drawing, making a part of this specification.

The drawing represents a perspective view of the stove and urn, the
back and end which is not seen being respectively the same as the front and end, repre-
-sented with the exception of a pipe-hole in the back plate and a door in the end.

The design of ornament is made up of scrolls, and a basket of fruit
on the front plate as represented.

Having thus described and represented my new design of
parlor stove.

What I claim as new and desire to secure by Letters Patent is the
design and configuration of ornament constituting a parlor stove substantially the same as herein described
and represented.

6.8.26. E. Bell. { Witnesses.
C. S. Brindage.

Wm L. Sanderson.
